US0D1044899S

(12) **United States Design Patent** (10) **Patent No.:** **US D1,044,899 S**
(45) **Date of Patent:** **** Oct. 1, 2024**

(54) **STORAGE ROBOT**

(71) Applicant: **HAI ROBOTICS CO., LTD.**,
Shenzhen (CN)

(72) Inventor: **Shaokai Zhou**, Shenzhen (CN)

(73) Assignee: **HAI ROBOTICS CO., LTD.**,
Shenzhen (CN)

(**) Term: **15 Years**

(21) Appl. No.: **29/801,076**

(22) Filed: **Jul. 26, 2021**

(30) **Foreign Application Priority Data**

May 12, 2021 (CN) 202130282838.5

(51) **LOC (14) Cl.** **15-99**

(52) **U.S. Cl.**

USPC **D15/199**; D34/34

(58) **Field of Classification Search**

USPC D34/28, 29, 34-37; D15/199;

(57) **CLAIM**

The ornamental design for a storage robot, as shown and described.

DESCRIPTION

FIG. 1 is a front right side perspective view of a storage robot;

FIG. 2 is a rear left side perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The claimed design is indicated by the relatively dark portions shown in the figures, while the relatively de-emphasized and light portions form no part of the claimed design.

1 Claim, 8 Drawing Sheets
